BEER DISPENSING DEVICE

Lee Orr, Alturas, Calif.

Application December 6, 1938, Serial No. 244,245

5 Claims. (Cl. 210—164)

This invention relates to a device for use in the dispensing of beer.

An object of the invention is to provide a device of this character which will enable one to dispense beer many times faster than is now the case with beer-dispensing systems embodying a coil.

A further object of the invention is to provide a device of this character which will eliminate all waste of agitated or wild beer under any temperature.

A further object of the invention is to provide a device of this character which is readily accessible for cleaning.

15 A further object of the invention is to provide a device of this character which may be interposed in the line from a source of supply to the dispensing faucet and which embodies a breaker screen which serves to break the air bubbles in 20 the beer, reducing such air bubbles substantially to the size of gas bubbles with a consequent reduction of agitation and the promotion of even flow of beer at the faucet.

The invention together with its objects and 25 advantages will be best understood from a study of the following description taken in connection with the accompanying drawings wherein—

Figure 1 is a side elevational view of the device.

30 Figure 2 is a longitudinal sectional view through the device.

Figure 3 is a transverse sectional view taken substantially on the line 3—3 of Fig. 1.

Figure 4 is an end elevational view of the device.

35 Figure 5 is a view showing in edge elevation a breaker screen and a cap or head for the drum together with a rod connecting said screen and head.

40 Figure 6 is a sectional view taken substantially on the line 6—6 of Fig. 5.

Figure 7 is a modified form of the device.

Figure 8 is a fragmentary view of the device with parts broken away and shown in section.

45 Figure 9 is an end elevational view of the device with parts broken away and shown in section, and

Figure 10 is a vertical transverse sectional view taken substantially on the line 10—10 of Fig. 7.

50 Referring to the drawings by reference numerals it will be seen that the device, in the preferred embodiment, comprises an elongated cylindrical tank 5 that is closed at one end and at its opposite end is provided with a removable cap 55 or head plate 6.

The cap or head plate 6 is secured in position on the open end of the drum 5 through the medium of bolts 7 that are accommodated by apertured lugs 8 provided on the peripheral wall of the drum or cylinder 5 inwardly from the open end of the latter as shown in Figure 2. Threadedly engaged with the bolts 7 are wing nuts 9 that are adapted to be threaded home against the outer side of the cap or head plate 6 to secure the latter in position.

10 On one face thereof the cap or head plate 6 is provided adjacent its periphery with a continuous groove 10 which receives a sealing gasket 11, as shown, and which is held in place between the cap 6 and the edge of the wall of the drum 5.

15 The drum 5 is supported through the medium of any suitable supports 12 disposed adjacent the opposite ends of the drum.

20 At the closed end thereof the drum 5 is provided with an inlet nipple 13 to which is coupled as at 14 one end of a beer conduit 15 leading from a source of supply.

25 Adjacent the open end thereof the drum 5 has depending from the bottom thereof an outlet nipple 16 to which is connected as at 17 one end 25 of a conduit 18 that leads to the dispensing faucet (not shown).

30 Removably positioned within the drum 5 and slightly spaced from the closed end of the drum 30 is a breaker screen 19.

35 In the present instance the screen 19 consists of a frame 20 of any suitable material which fits conformally within the drum 5 and mounted within the frame 20 is a disk 21 of screening or other reticulated material.

40 Permanently secured, in any suitable manner, to the disk 21 at the center thereof is one end of a rod 22. Rod 22 at its opposite end is also secured permanently, and in any suitable manner, to the head plate or cap 6.

45 It will thus be seen that as the cap 6 is positioned on the open end of the drum 5 the screen 19 is properly positioned within the drum 5 adjacent to the closed end of the drum. Likewise, upon removal of the cap 6, the screen 19 may be 45 readily withdrawn from the drum.

50 In actual practice the beer flows from the source of supply through the line 15 entering the drum 5 at 13. The beer passes, within the drum, through the screen 19 flowing lengthwise 50 of the drum to discharge therefrom at the outlet 16. From the drum 5 the beer passes through the conduit 18 to the faucet.

55 In actual practice the screen 19 will serve to break up the air bubbles in the beer, reducing

such bubbles to the size of gas bubbles (CO_2) thereby reducing agitation and insuring an even flow of the beer at the faucet.

In the construction shown in Figures 7 to 10 the cylindrical drum 23 has one end thereof closed and its opposite end is provided with a removable cap or head plate 24. The lower side wall of the drum 23 is corrugated as shown at 23' while the upper side has a relief valve A mounted therein.

The cap or head plate 24 is secured in position on the open end of the drum 23 through the medium of bolts 25 that are accommodated by apertured lugs 26 provided on the peripheral wall of the drum 23 inwardly from the open end of the latter as shown in Figure 8. Threadedly engaged with the bolts 25 are wing nuts 27 that are adapted to be threaded home against the outer side of the cap or head plate 24 to secure the latter in position.

On one face thereof the cap or head plate 24 is provided adjacent its periphery with a continuous groove 27 which receives a sealing gasket 28, as shown, and which is held in place between the cap 24 and the edge of the wall of the drum 23.

At the closed end thereof the drum 23 has projecting therefrom a corrugated tube 29 which is closed at its outer end and communicates with the drum at its opposite end as shown in Figure 8.

The cap 24 has mounted therein a float controlled inlet valve 30 which is connected to one end of a beer conduit 31. The other end of the conduit 31 is connected to a source of supply 32 which is controlled by a valve 33.

At the closed end thereof the corrugated tube 29 is provided with an outlet nipple 34 to which is coupled as at 35 one end of a beer conduit 36 that leads to a dispensing faucet (not shown).

Removably positioned within the drum 23 and slightly spaced from the closed end of the drum is a breaker screen 37.

The screen 37 consists of a frame 38 of any suitable material which fits conformably within the drum 23, and mounted within the frame 38 is a disk of screening 39.

Permanently secured, in any suitable manner, to the disk 39 at a point near one edge thereof is one end of a rod 40. Rod 40 at its opposite end is also secured permanently, and in any suitable manner, to the head plate or cap 24.

It will thus be seen that as the cap 24 is positioned on the open end of the drum 23 the screen 37 and float controlled inlet valve 30 are properly positioned within the drum 23.

A conduit 41 leading from a source of compressed air (not shown) is connected to the beer supply 32 as at 42 and has communicating therewith at an intermediate point therein a conduit 43 for conveying the compressed air to the drum 23 for completely discharging the beer from the same when the control valve 33 is closed to cut off the beer supply from the source 32 to the drum 23. A manually controlled valve 44 is mounted 65 in the conduit 43 for controlling the passage of the compressed air therethrough.

In actual practice the beer flows from the source of supply through the line 31 entering the drum through the float controlled valve 30. The beer 70 passes, within the drum 23, through the screen 37 flowing lengthwise of the drum to discharge therefrom into the corrugated tube 29 and out through the conduit 36 to the faucet.

It is believed that a full understanding of the construction, utility and advantages of an inven-

tion of this character will be had without a more detailed description.

Having thus described the invention what is claimed as new is:

1. A device for disposition with a beer line intermediate the source of supply and a faucet, said device comprising an elongated cylindrical drum provided with an inlet and an outlet and one end of the drum being open, a removable head plate for the open end of the drum, a breaker screen 10 for disposition within said drum, and an elongated rod secured at one end thereof to the screen and at an opposite end thereof to said head plate, said drum adjacent the open end thereof provided internally with apertured lugs, and said 15 head plate being provided with apertures to register with the apertures in said lugs, bolts extending outwardly from the drum through said lugs and the apertures in said head plate, and wing nuts threadedly engaged with the outer ends of 20 said bolts for securing the head plate in position at the open end of the drum.

2. A device for disposition with a beer line intermediate the source of supply and a faucet, said device comprising an elongated cylindrical drum 25 having one end open and the other end being closed and having an opening in its lower part, an elongated tubular member having one end in communication with the drum through said opening in the closed end thereof, the other end of the 30 tubular member being closed, outlet means adjacent the closed end of the tubular member, a plate closing the open end of the drum, means for detachably holding the plate in position, a screen extending across the drum, a rod connecting the 35 screen with the plate and means for connecting the drum with the source of supply.

3. A device for disposition within a beer line intermediate the source of supply and a faucet, said device comprising a drum having one end open 40 and its other end closed but said closed end having a small opening in its lower part, a tubular member of elongated form having one end in communication with the drum through said opening and the other end of the tubular member being 45 closed, outlet means connected with the closed end of the tubular member, a closure plate detachably connected with the open end of the drum, a screen extending transversely across the 50 drum, a rod connecting the screen with the closure plate, inlet means carried by the closure plate and including a float operated valve located within the drum.

4. A device for disposition within a beer line intermediate the source of supply and a faucet, 55 said device comprising a drum having one end open and its other end closed but said closed end having a small opening in its lower part, a tubular member of elongated form having one end in communication with the drum through said opening and the other end of the tubular member being 60 closed, outlet means connected with the closed end of the tubular member, a closure plate detachably connected with the open end of the drum, a screen extending transversely across the 65 drum, a rod connecting the screen with the closure plate, inlet means carried by the closure plate and including a float operated valve located within the drum, the lower part of the drum and the tubular member being longitudinally corrugated.

5. A device for disposition within a beer line intermediate the source of supply and a faucet, said device comprising a drum having one end open and its other end closed but said closed end having a small opening in its lower part, a tubu-

lar member of elongated form having one end in communication with the drum through said opening and the other end of the tubular member being closed, outlet means connected with the closed end of the tubular member, a closure plate detachably connected with the open end of the drum, a screen extending transversely across the drum, a rod connecting the screen with the closure

plate, inlet means carried by the closure plate and including a float operated valve located within the drum, and means for introducing compression fluid into the drum through the closure plate to force liquid from the drum and the tubular member to empty said drum and tubular member. 5
